United States Patent Office

Des. 196,638
Patented Oct. 22, 1963

196,638

PORTABLE MIXING MACHINE

Orrie V. Parker and Gordon L. Parker, R.R. 2, and Bill
Hammontree, 415 Oxford St., all of Homer, Mich.

Filed Jan. 28, 1963, Ser. No. 73,339

Term of patent 3½ years

(Cl. D14—3)

Fig. 1

*Fig. 2**Fig. 3*

FIGURE 1 is a perspective view of a portable mixing machine embodying our new design, the opposite side of same having the same appearance.

FIGURE 2 is a rear elevation thereof.

FIGURE 3 is a front elevation thereof.

We claim:

The ornamental design for a portable mixing machine, substantially as shown and described.
